UNITED STATES PATENT OFFICE.

MORDECAI SEGAL, OF WACO, TEXAS.

DETACHABLE DRAFT APPLIANCE.

SPECIFICATION forming part of Letters Patent No. 726,769, dated April 28, 1903.

Application filed January 19, 1903. Serial No. 139,635. (No model.)

To all whom it may concern:

Be it known that I, MORDECAI SEGAL, a citizen of the United States, residing at Waco, in the county of McLennan and State of Texas, 5 have invented certain new and useful Improvements in Detachable Draft Appliances; and I do hereby declare the following to be a full, clear, and exact description of the invention, such as will enable others skilled in 10 the art to which it appertains to make and use the same.

My invention relates to improvements in detachable draft-rigging for vehicles; and it consists of certain novel improvements and 15 features of construction, whereby the whole rigging may be readily detached from the running-gear from a convenient position adjacent the wagon-seat.

The principal object of my invention is to 20 provide a ready means for releasing the horse or horses from the wagon-body, if they become unmanageable, and thus materially decreasing the danger from runaways.

To more fully describe my invention reference is had to the accompanying drawings, 25 in which like letters refer to like parts in the several views, and in which—

Figure 1 is a perspective view of a portion 30 of a wagon-body and shafts having my device applied thereto. Fig. 2 is a detail view, in perspective, of the detaching member. Fig. 3 is a detail view showing means on the rear of the dashboard for securely holding the detaching member in position, and Fig. 35 4 is a sectional detail showing the connection between the shafts and the axle.

A is the dashboard or front of the wagon-body, B the axle, and C the shafts.

D represents horizontally-disposed supports, substantially of the form shown and 40 preferably rigidly secured near the ends of the axle by means of the fastening bands or loops D' and the bolts E, passing through a suitable aperture in the band D' into the axle-body. These supports D are preferably made 45 of suitable flat metal and are provided on their outer ends with the channelled or grooved projections D⁰, formed by the extension of the flat metal strips and the upwardly-extending rear and side flanges d d'. The supports D are apertured at d⁰ in the channelled projection D⁰ to receive a suitable fastening-

pin carried by the detaching member herein-after described.

The shafts are provided at their inner ends 55 with the hinged or pivotal member E', one end of which is rigidly secured to the shaft ends and the other free end adapted to be inserted in the channelled projection D⁰ of the supports D and held in position therein by 60 the aforementioned pins of the detaching member passing through a suitable perforation e in the free end of the hinged member.

The detaching member above referred to 65 comprises the cross-piece F, disposed transversely of the wagon-body and provided at each end with the fastening-pins f, adapted to engage the perforations d⁰ and e for the purpose above described. This cross-piece F is provided with the central longitudinally-disposed slot F⁰, and in this slot is mounted 70 the lower end of the operating-rod G, held therein by a suitable washer and nut g g'. The rod G is of substantially the shape shown and is partly supported in a vertical position 75 by the perforated support H on the wagon-body, which guides the same and prevents the rod from buckling when shoved down to its locked position. The upper end of the rod G is preferably bent over, as shown, to 80 form a looped end G', leaving a space g⁰ between the end of the loop and the rod proper. This space g⁰ is sufficiently large to allow of the passage of the dashboard therethrough.

The object of the slot F⁰ in the cross-piece 85 F is to allow the lower end of the rod G to ride therein when the shafts are moved in a horizontal plane, and thus allow the front wheels of the wagon to turn on the king-pin or fifth-wheel, as the case may be.

In order that the detaching member may be 90 detachably secured rigidly in position and the pins correspondingly held rigidly in position, I provide suitable means engaging the rod G and within easy reach of the driver.

In the drawings I have shown the snap-hook I pivotally secured at i to the dashboard, the hooked end I' being adapted to engage the lower portion of the loop G', and if the loop G' is of the proper length the detaching member will be held rigidly in position. I² represents the spring-actuated member of the snap-hook I.

The operation of the device is as follows:

The detaching member being held rigid in position, as shown in Fig. 1, by means of the snap-hook I, Fig. 3, when the horse becomes unmanageable and it is desired to release the 5 animal the spring member I^2 is depressed and the hook I' thrown out of engagement with the looped end G' of the bar G. The bar G may then be raised, and with it the transverse cross-piece F, and the lugs or pins f 10 withdrawn from the apertures e d^0 , thus disengaging the shafts, carrying the singletree, from the body of the wagon.

I have only shown my improved device as applied to a wagon or carriage adapted for 15 use with a single horse; but it is manifest that with a few slight changes it may be made equally applicable to a wagon using a tongue for teamwork.

Many other modifications might also be 20 made without departing from the spirit of my invention; but

What I claim, and desire to secure by Letters Patent of the United States, is—

1. The combination with a wagon, of supports carried by the axle thereof, draft-rigging adapted to engage said supports, a cen- 25

trally-slotted cross-piece extending transversely between said supports, means carried by said cross-piece for locking said draft-rigging and supports together, and a rod engaging said cross-piece in said slot and adapted to be operated from the seat of the wagon for unlocking said locking means and disengaging said draft-rigging from said supports. 30

2. The combination with a wagon, of supports carried by the axle thereof provided with channeled ends, shafts having inner ends adapted to engage said channeled ends, apertures through said shaft ends and said channeled supports, a cross-piece extending transversely between said supports, pins on said cross-piece adapted to engage said apertures, and means engaging and co-operating with said cross-piece for holding said pins in said apertures and withdrawing same when de- 40 sired. 45

In testimony whereof I affix my signature in presence of two witnesses.

MORDECAI SEGAL.
